(57) **CLAIM**

The ornamental design for a bag for stroller, as shown and described.

DESCRIPTION

FIG. 1 is an upper and right side perspective view of a bag for stroller showing the new design;

FIG. 2 is an upper plan view thereof;

FIG. 3 is a front elevation view thereof;

FIG. 4 is a rear elevation view thereof;

FIG. 5 is a left side elevation view thereof; and,

FIG. 6 is a left side elevation thereof showing the environment of the bag for stroller when used with a stroller.

The broken lines illustrate environment for the bag for stroller and form no part of the claimed design.

1 Claim, 4 Drawing Sheets
